UNITED STATES PATENT OFFICE

JOHN L. PUTZEL, OF BALTIMORE, MARYLAND

ARCH-SUPPORT SHOE

Application filed September 12, 1927. Serial No 218,964.

The object of this invention is to provide an efficient and well-placed rigid arch support, especially for high-heeled shoes, so designed as to adequately sustain the arch 5 of the foot of the wearer.

The invention consists of an arch supporting shoe shank piece or stiffener, of rigid metal, shaped longitudinally and transversely so as to sustain corresponding pressures 10 of a wearer's foot and extending from the heel to a point forward in the shoe corresponding substantially with the hollow of the foot, and secured at both points, and cushioned at its forward portion, as I will 15 proceed now more fully to explain and finally claim.

In the accompanying drawings illustrating the invention, in the several figures of which like parts are similarly designated, 20 Figure 1 is a bottom plan view of a shoe, with the heel and outer sole omitted. Fig. 2 is a side elevation of a shoe partly in section. Fig. 3 is a top perspective view of the shank piece or stiffener. Fig. 4 is a perspective 25 view of the cushion. Fig. 5 is a cross-section of the shank, detached, taken on line 5—5 of Fig. 3.

The upper 1, insole 2, welt 3, sole 4, filling 30 5 and heel 6 may be of any usual or approved construction, excepting that at the arch or hollow of the shoe the parts may be drawn in from about 7 to 7', to fit the foot con- 35 formation snugly and without liability to fullness or wrinkling.

The rigid shank piece or stiffener,—see for 40 details Fig. 3—comprises the heel portion 8, having the tack-receiving holes provided with the burrs 9, which by entering the insole aid in securing that end of the shank piece or stiffener in place; the elongated 45 arched portion 10, provided with the reinforcing rib 11, and the laterally extending end 12, having the horn 13 curved inwardly to conform to the curvature of the inner 50 side of the shoe, and the horn 14 of less extent than the horn 13 and curved to conform to the outer side of the shoe, each horn being provided with a tack-hole having its inner edge burred, as at 15 and 16, respectively, so as to enter the material of the sole and assist

the tacks in holding the shank piece or stiffener in place; and an opening 17, provided with a prong 18 which also enters the material of the sole.

The shank piece or stiffener is not only 55 curved lengthwise but also crosswise, so as to conform to the foot curvature to which the shoe is fitted, and its rib 11 is located on the outside and not directly in the middle, and thereby the shank piece or stiffener may 60 come up higher on the inside arch, thus throwing the weight of the wearer more to the outside and permitting the bringing of the inside close to the inside arch of the foot.

The shank piece or stiffener is made, pref- 65 erably, of sheet steel, died and pressed to shape and hardened to a sufficient degree to make it rigid. It is so molded or pressed as to come up higher on the inside of the 70 shoe than on the outside, in order to conform to the arch of the foot of the wearer and the last on which the shoe is made.

The shank piece or stiffener extends back 75 of the break line or ball and not under the same, and thereby tends to keep the support of the foot back of the metatarsal heads or joints and not under them, thus permitting the foot and shoe to flex freely; it being understood that the second, third and fourth 80 metatarsal heads or joints are not weight-bearing areas.

A pad, 19, of rubber or other yielding material, is arranged on the insole so as to serve as a cushion for the forward end of 85 the shank piece or stiffener, and this cushion is of a contour, breadth and length and of substantially conoidal transverse section, so as to underlie the forward portion of the arch portion and extend beyond the end 12, as shown in Figs. 1 and 4.

The provision of the cut-out 17 and the use of the specially constructed yielding pad or cushion admits of the production of a 90 springy metatarsal support which allows normal metatarsal arch functioning. The insole coming up higher on the inside furnishes more support to the inner longitudinal arch than prior arch support shoes of usual construction so far as I am aware. This 95 support is carried forward to a point directly 100

behind the location of the great toe joint, and thus will tend to restore the normal posture in standing and walking; that is, the foot straight forward toeing in slightly. In addition to this, through the described construction and the shape of the shank piece or stiffener, the outer longitudinal arch gets a similar support. The insole being flexible and wider than the outsole, shapes itself to the contour of the foot when the shoe is fastened. The insole 2 is wider on the inside of the shoe than the outer sole 4, for the purpose of acting as an additional inner support for the inner longitudinal arch of the foot, and it is held in place by the shank piece or stiffener, which, as stated, is molded or pressed higher on the inside, for this and other purposes. These features contribute to making an anatomically correct shoe.

20 When the shank piece or stiffener and the cushion are arranged as shown in Figs. 1 and 2, the shank piece or stiffener is secured in position by nailing, the burrs and the prong 18 sinking into the adjacent material and thereby assisting the tacks in holding the shank piece or stiffener in position.

It will be understood, of course, that the shank pieces or stiffeners are made as rights and lefts to accommodate shoes of that character.

As will be seen the edges of the cushion are bevelled so that the cushion may be cemented and held in place on the bottom of the insole.

35 By the construction described the arch of high heel shoes particularly, may be adequately supported so as to increase the comfort of the wearer, and this is equally true of low heel shoes.

40 As already stated, the construction permits of drawing the upper inwardly to ensure the fit of the shoe and prevent wrinkling or undesirable fullness in the arch.

45 Variations in details of construction are permissible within the principle of the invention and the claims following.

What I claim is:—

1. An arch support shoe, provided with a shank piece or stiffener of rigid material 50 curved longitudinally and transversely to conform to the arch of the shoe and extending from the forward portion of the heel of the shoe to the break line of the shoe and provided at its forward end with laterally 55 extending horns, the forward portion having an opening, and a cushion underlying said opening and the forward end of the shank piece or stiffener.

60 2. An arch support shoe, provided with a shank piece or stiffener of rigid material curved longitudinally and transversely to conform to the arch of the shoe and extending from the forward portion of the heel of the shoe to the break line of the shoe and 65 provided at its forward end with laterally

extending horns, the forward portion having an opening and a prong extending inwardly from said opening.

3. An arch support shoe, having a shank piece or stiffener, made of rigid material and curved longitudinally and transversely to conform to the arch of the shoe and extending from the forward portion of the heel of the shoe to the break line, and provided at its forward end with laterally extending horns and an opening between said horns, and a longitudinal rib interposed between the heel portion and the forward portion and toward the outer side of the longitudinal center of the shank piece or stiffener, said shank piece or stiffener coming up higher on the inside of the arch than on the outside.

In testimony whereof I have hereunto set my hand this 10th day of September, A. D. 1927.

JOHN L. PUTZEL.
